UNITED STATES PATENT OFFICE.

RUFUS MELVIN OVERLANDER, JR., AND EVARTS WEBSTER OVERLANDER, OF NEW YORK, N. Y.

DESIGN FOR A HOLDER FOR WATCH AND CLOCK MOVEMENTS.

Application filed May 10, 1928. Serial No. 28,626. Term of patent 14 years.

To all whom it may concern:

Be it known that we, RUFUS MELVIN OVERLANDER, Jr., and EVARTS WEBSTER OVERLANDER, citizens of the United States, residing at 239 East 176th Street, New York city, in the county of New York and State of New York, jointly have invented a new, original, and ornamental Design for Holder for Watch and Clock Movements, of which the following is a specification, reference being

had to the accompanying drawing, forming a part thereof.

The figure is a perspective view of a holder for watch and clock movements, showing our new design.

We claim:

The ornamental design for a holder for watch and clock movements, as shown.

RUFUS MELVIN OVERLANDER, Jr.
EVARTS WEBSTER OVERLANDER.
